(57) **CLAIM**

The ornamental design for an adjustable pedestal as shown and described.

DESCRIPTION

FIG. 1 is a perspective view of an adjustable pedestal in a lowered position showing my new design;

FIG. 2 is a right side view thereof;

FIG. 3 is a front view thereof;

FIG. 4 is a left side view thereof;

FIG. 5 is a rear view thereof;

FIG. 6 is a top view thereof;

FIG. 7 is a bottom view thereof;

FIG. 8 is a perspective view of an adjustable pedestal in a raised position;

FIG. 9 is a right side view thereof;

FIG. 10 is a front view thereof;

FIG. 11 is a left side view thereof; and,

FIG. 12 is a rear view thereof.

The broken lines in the drawings depict structure that makes up no part of the claimed design.

1 Claim, 12 Drawing Sheets
